US00D379748S

United States Patent [19]

Reekie et al.

[11] Patent Number: Des. 379,748

[45] Date of Patent: **Jun. 10, 1997

[54] STRING TRIMMER

[75] Inventors: George Reekie, North York; Jacob Prosper, Brockville, both of Canada

[73] Assignee: Black & Decker Inc., Newark, Del.

[**] Term: 14 Years

[21] Appl. No.: 30,023

[22] Filed: Oct. 20, 1994

[51] LOC (6) Cl. 08-01

[52] U.S. Cl. D8/8

[58] Field of Search D8/8; 56/12.7; 30/276

[57] CLAIM

The ornamental design for a string trimmer, as shown.

DESCRIPTION

FIG. 1 is a left side perspective view of a string trimmer in accordance with present invention;

FIG. 2 is a right rear perspective view of the string trimmer shown in FIG. 1;

FIG. 3 is a right side view of the string trimmer shown in FIG. 1;

FIG. 4 is a front view of the string trimmer shown in FIG. 1;

FIG. 5 is a left side view of the string trimmer of FIG. 1;

FIG. 6 is a rear view of the string trimmer of FIG. 1;

FIG. 7 is a top view of the string trimmer of FIG. 1; and,

FIG. 8 is a bottom view of the string trimmer of FIG. 1. The broken line showing of outlet prongs and of trimmer cutting assembly is for illustrative purposes only and forms no part of the claimed design.

1 Claim, 4 Drawing Sheets

FIG. 2.

FIG. 3.
